UNITED STATES PATENT OFFICE.

EDWARD B. CADY, OF JACKSON, MICHIGAN.

BUSTLE.

SPECIFICATION forming part of Letters Patent No. 322,678, dated July 21, 1885.

Application filed February 27, 1885. (No model.)

To all whom it may concern:

Be it known that I, EDWARD B. CADY, a citizen of the United States, residing at Jackson, in the county of Jackson and State of Michigan, have invented certain new and useful Improvements in Bustles, of which the following is a specification.

My invention relates to an improvement in bustles or panniers; and it consists in providing a bustle or pannier with a novel compound spring made of wire having a cover, the wire and cover being inclosed in a soft fibrous envelope, which is secured by a row of stitching through both said soft envelope and the cover on the wire.

The construction of the compound spring and its embodiment or combination in a bustle or pannier will first be described, and the invention then designated in the claim.

The invention is illustrated in the accompanying drawings, in which Figure 1 is a view of the wire spring and its cover. In this instance two wires have the same cover. Fig. 2 is a view of the wire spring and cover, this modification showing one wire only. Fig. 3 is a view of the covered wire spring inclosed and secured in the soft envelope. Fig. 4 is a cross-section of the same. Figs. 5, 6, and 7 are views of the covered wire spring and soft envelope having its end tipped. Fig. 8 is a vertical section (side view) of a bustle or pannier to which the compound springs are attached. Fig. 9 is a front or inside view of the bustle or pannier.

The compound spring is shown in Figs. 3 and 4.

The letter *a* designates a spring-wire, which may be straight or spiral, and if straight may be a flat or a round wire. One or more of these wires are covered, as at *b*, by folding around them a narrow strip of woven fabric, paper, or leather, or both paper and woven fabric, but preferably cotton cloth, and stiffening as well as securing said cover by means of glue or a suitable size. If one wire only is used the stiffened cover should project or form a flange, *b'*, along one edge of the wire, as seen in Fig. 2. If two wires, *a*, are used, the stiffened cover should form a thin center web, *b''*, between the two wires. In either case the wire should be held firmly and solidly by the glue-stiffened cover. The flange *b'*, if one wire

is used, or the center web, *b''*, if two are used, form a "stitch-surface" at one side of the wire, which serves to receive a row of stitches, as 55 hereinafter described, by which the outer envelope is secured. The covered spring-wire, being in suitable lengths for the bustle or pannier, is next enveloped, as at *c*, in a light soft material, such as raw-cotton, felt, or shoddy, 60 or any suitable fibrous material. This envelope *c*, of soft fibrous material, is wound or applied in any convenient manner about the covered wire, and is secured by a row of stitches, *d*, through both the envelope and the stitch-surface of the covered wire. To still further 65 improve the compound spring, each end may be provided with a tip, *e*, of leather, paper, or cloth, preferably leather, which is secured either on the extremity of the envelope by its 70 two ends, *e'*, lapping on opposite sides of the envelope, as seen in Figs. 5 and 6, or on the extremity of the stitch-surface, as in Fig. 7. The same row of stitches *d* which secures the envelope *c* to the covered wire may also secure the tip, as shown in Fig. 5; or it may be secured by a rivet, as in Fig. 7, by passing through the overlapping ends *e'*. By this construction of and mode of attaching the end tip the ends of the wires cannot force themselves 80 through the fabric of the bustle, and the tip *e*, which is left projecting at the extremity, serves to receive the stitches, as hereinafter stated, which hold the compound spring in position in the bustle.

The bustle, pannier, or like article is provided with parallel tubes or pockets *f*, made in any well-known manner and finished, excepting one end, which is unclosed, and one of the above-described compound springs *a c* is 90 readily inserted endwise in the unclosed end of each tube. The unclosed end of each tube is then fastened by a row of stitches, *g*, which pass also through the projecting tips *e* on the compound springs. A flap or narrow apron, 95 *H*, is then sewed on each side of the bustle, and each flap has eyelets *i*. An elastic cord, *k*, is laced through the eyelets of the two flaps, and by it the flaps are drawn toward each other or adjusted at such position as will give the desired bow or curvature to the springs in the bustle.

A bustle or pannier thus constructed and provided with the compound springs will yield

to any pressure to which it may be subjected without injury to the material composing the bustle or the tubes, and at the same time these 5 springs afford the requisite resistance to insure the return of the bustle to the original shape the moment the pressure is relieved. While the compound spring is thus very efficient, it is also well adapted, because it gives to the bustle a soft and smooth exterior, and the wear 10 on the fabric composing the tubes is reduced to a minimum. The nature of the compound spring is such that there will not be any curling or collapsing of the bustle parts at or near the ends of the tubes—a result particularly 15 desirable to avoid.

Having described my invention, I claim and desire to secure by Letters Patent of the United States—

A bustle, pannier, or like article having in combination a wire, a glue-stiffened cover firmly and solidly holding the wire and forming at one side thereof a flange or stitch-surface, and an envelope of light soft material, such as raw cotton, wound around the said covered wire and its glue-stiffened flange and secured thereto by stitches passed through both the soft envelope and stitch-surface, as set forth.

In testimony whereof I affix my signature in presence of two witnesses.

EDWARD B. CADY.
